BUTTON ATTACHING MACHINE CO., OF NEW YORK, N. Y., A CORPORATION OF NEW
YORK.

BUTTON-FEEDING MECHANISM.

1,204,067.

Specification of Letters Patent.

Patented Nov. 7, 1916.

Application filed July 7, 1915. Serial No. 38,587.

To all whom it may concern:

Be it known that I, CHARLES F. RICHARDSON, a citizen of the United States, and a resident of Woonsocket, in the county of Providence and State of Rhode Island, have invented a new and Improved Button-Feeding Mechanism, of which the following is a full, clear, and exact description.

This invention relates to a button feeding mechanism, and more particularly to means for picking up buttons and supplying them in a definite manner to a feeding chute which delivers the buttons one at a time to a suitable attaching mechanism, whereby buttons are attached to the uppers of a shoe or other article.

The invention has for its general object to improve and simplify the construction of button pick-up devices so as to be reliable and efficient in use, comparatively simple and inexpensive to manufacture, and so designed as not to readily get out of adjustment.

A further object of the invention is the provision in connection with a button hopper having a vertically reciprocatory pick-up device, of means for insuring the proper flow of the buttons from the said device to the button feeding chute, such means being a clearing or anti-clogging element which is operated simultaneously with the pick-up device for preventing the clogging of buttons at the top of the chute where the device supplies them to the latter.

With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention and wherein similar characters of reference indicate corresponding parts in all the views, Figure 1 is a side view of a button attaching machine having the invention applied thereto; Fig. 2 is an enlarged view, partly in section, of the button hopper pick-up device and anti-clogging means; Fig. 3 is a plan view of the structure shown in Fig. 2; Figs. 4 and 5 are detail sectional views on the lines 4-4 and 5-5, respectively, Fig. 2; Fig. 6 is a transverse section of the hopper with the pick-up device in its lowermost

position; and Fig. 7 is a perspective view of the pick-up device.

Referring to the drawing, A designates a button-holding hopper in which vertically reciprocates a pick-up device B which moves up and down through a mass of buttons contained in the hopper and picks up one or more buttons to discharge them in a predetermined position to a feed chute C down which the buttons flow by gravity to the attaching mechanism of the machine, such mechanism not being disclosed herein, as it forms no part of the present invention. The hopper is a suitably shaped receptacle having a bottom 1 which slopes laterally 70 from the side wall 2 to the opposite side wall 3, and also slopes rearwardly from the front portion 4 to the rear wall 5. The top of the hopper is normally closed by a door 6 which swings on a horizontal pintle 7 attached to the front of the hopper. At the rear lowermost portion of the hopper is an opening 8 which is closed by a door 9 that is adapted to open when the hopper is to be discharged of its contents. The hopper 80 is carried by the upper rear portion of the chute C, and in the bottom of the hopper is an opening 10 through which the pick-up device B reciprocates, such device being located adjacent to a side wall 3.

The pick-up device B is a vertically disposed plate of approximately segmental form and it is provided with a forwardly extending arm 11 which extends forwardly into the chute C, where it is pivoted at 12 90 to the chute, the rear edge 13 of the chute being concentric with the pivot 12, as is also the forward edge of the pick-up device, the rear edge of the pick-up device being curved to conform to the rear curved wall 5 95 of the hopper. In the top edge of the pick-up device is a longitudinal channel or groove 14, the edges of which are beveled at 15, so that the eyes or shanks 16 of the shoe or other buttons 17 can enter the channel, 100 while the heads will rest on the top edge of the pick-up device at opposite sides of the channel, as shown by dotted lines in Fig. 4. This channel 14 alines with the slot 18 in the top edge of the chute C, so that the buttons can flow by gravity off the pick-up device into the chute, the upper portion of the latter extending into the hopper, as clearly shown in Figs. 2 and 3. The pick-up device is reciprocated by a lever 19 fulcrumed at 110

20 on the frame D of the machine, and on the free end of the lever is a pin 21 which engages in a slot 22 so disposed in the bottom of the pick-up device that, as the lever 5 oscillates, the pick-up device will swing up and down around the pivot 12 as a center. The lever 19 is operated by a pedal, not shown, which operates the button attaching mechanism, the pedal serving to move up- 10 wardly a rod 23 in the pillar 24 of the machine, which rod is connected through a lever 25, a link 26, connected arms 27 and 28, and a link 29, with the lever 19. The operating connections between the rod 23 and 15 the attaching mechanism are not shown, as they are unnecessary to an understanding of the present invention.

To prevent buttons from clogging the upper or receiving portion of the chute C, an anti-clogging or clearing device E is employed. This comprises a kick-off or finger 30 which is fulcrumed in the upper part of the chute C and swings upwardly from the full-line position, Fig. 2, to the dotted-line 20 position. The extremity 31 should move back and forth in the slot 18. This finger swings on a center 32 so located that when the finger is in forward or lowered position, as shown by full lines, the buttons can freely 25 pass down the chute, but when the finger moves upwardly it kicks off any buttons which may be lodged on the upper portion of the chute disposed in the hopper. The pivot 32 of this finger has fastened thereto 30 an arm 33 which is disposed outside the chute and hopper, and on the pivot is a coiled spring 34 having one end 35 engaged with a pin 36 on the arm 33, whereby the spring tends to throw the arm 33 downwardly and the finger 30 upwardly from the 35 full to the dotted line position, Fig. 2. The clearing or kick-off device E is operated in the opposite direction by an arm 37 which has one end fastened to the pivot 12 on 40 which the pick-up device swings, and the other end of the arm or lever 37 is provided with a laterally extending pin 39 that engages under the arm 33 so as to release the latter as the pick-up device ascends. 45 Above that portion of the chute C in which the clearing finger 30 operates is a beveled abutment 40 so as to deflect those buttons which may attempt to feed down the chute while they are supported on other buttons. 50 The bottom of this deflecting abutment 40 is disposed sufficiently above the top edge of the chute C that a single line of buttons can freely pass thereunder. Just below the abutment 40 an opening 41 is provided in 55 the front of the hopper so that the buttons can pass out from the latter and flow down the chute C. The portion of the chute behind the opening 41 is beveled at 42 so that those buttons which do not have their 60 shanks entered in the channel 14 of the pick- 65

up device will drop back into the hopper, since there is not sufficient support on the chute where the bevel 42 is located, to support the buttons that do not have their shanks entered in the channels 14 or 18. 70

Thus, there are three means for insuring against buttons clogging the outlet of the hopper, namely, the finger 30 of the device E, the deflecting abutment 40, and the bevel 42, and as the pick-up device has only a single channel and the top edge of the device is comparatively narrow, all the buttons that are properly picked up will be in a line and flow into the chute when the pick-up device reaches its uppermost position, as 75 shown in Fig. 2, where the top edge is considerably inclined to insure the ready flow of the buttons.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within 95 the scope of the appended claims.

Having thus described my invention, I claim as new and desire to secure by Letters Patent:

1. A button feeding mechanism comprising a chute having a slot for receiving the shanks of buttons, a pick-up device having a channel adapted to align with the slot of the chute, a hopper in which the pick-up device is mounted, means for actuating the pick-up device to cause the shanks of buttons in the hopper to engage in the channel of the pick-up device, said hopper having an outlet for permitting buttons to flow down the chute, a swinging finger movable back and forth in the slot of the chute to prevent clogging at the outlet of the hopper, and means for operating the finger simultaneously with the pick-up device. 100

2. A button feeding mechanism comprising a chute having a slot for receiving the shanks of buttons, a pick-up device movable curvilinearly in a vertical plane from a point below to a point above a horizontal and having a channel adapted to align with the slot of the chute, a hopper in which the pick-up device is mounted, means for actuating the pick-up device to cause the shanks of buttons in the hopper to engage in the channel of the pick-up device, said hopper having an outlet for permitting buttons to flow down the chute, a swinging finger movable back and forth in the upper part of the slot of the chute to prevent clogging of the outlet of the hopper, and means for actu- 115 120 125 130 135

ating the finger as the pick-up device operates.

3. A button feeding mechanism comprising a chute having a slot for receiving the shanks of buttons, a pick-up device having a channel adapted to aline with the slot of the chute, a hopper in which the pick-up device is mounted, means for actuating the pick-up device to cause the shanks of buttons in the hopper to engage in the channel of the pick-up device, said hopper having an outlet for permitting buttons to flow down the chute, a swinging finger movable back and forth in the upper part of the slot of the chute to prevent clogging of the outlet of the hopper, a spring means operating on the finger to move the same in one direction, and connecting means between the pick-up device and finger for moving the latter in the other direction.

4. A button feeding mechanism comprising a chute having a slot for receiving the shanks of buttons, a pick-up device having a channel adapted to aline with the slot of the chute, a hopper in which the pick-up device is mounted, means for actuating the pick-up device to cause the shanks of buttons in the hopper to engage in the channel of the pick-up device, said hopper having an outlet for permitting buttons to flow down the chute, a swinging finger movable back and forth in the upper part of the slot of the chute to prevent clogging of the outlet of the hopper, a spring-actuated arm for moving the finger in one direction, and an arm connected with the pick-up device and having a wiping engagement with the first-mentioned arm for moving the finger in the opposite direction.

40 5. A button feeding mechanism comprising a hopper, a chute leading therefrom and having a slot, a plate movable vertically in the hopper from the bottom to the top thereof, and vice versa, the top edge of the plate being grooved to receive the shanks of but-

tons and carrying the latter upwardly toward the top of the hopper, whereby buttons slide into the chute, a device movable upwardly into the path of the buttons and downwardly therefrom at the upper portion 50 of the chute for preventing clogging of the buttons, and a deflector disposed over the chute for preventing buttons discharged from the plate from being supported one on top of another.

55 6. A button feeding mechanism comprising a hopper, a chute on which the hopper is mounted and for receiving buttons from the latter, a vertically movable pick-up plate disposed in the hopper and pivotally connected with the chute at a point outside the hopper, means for actuating the pick-up device, and means actuated by the pick-up device for preventing buttons from clogging the outlet of the hopper and upper part of 60 the chute.

7. A button feeding mechanism comprising a chute, a hopper mounted on the chute and having the upper receiving portion of the latter disposed therein, a reciprocatory 70 plate having an arm extending into the chute and pivotally connected with the latter, the upper edge of the plate being longitudinally grooved to receive the shanks of buttons, means for actuating the plate, a finger movable back and forth for preventing the clogging of buttons on the upper portion of the chute, an arm connected with the finger, an arm connected with the pivot of the pick-up device to move with the latter, said arms 75 80 being interengaged for moving the first arm by the second, and means acting on the finger to impart return movement thereto.

In testimony whereof I have signed my name to this specification in the presence of 85 two subscribing witnesses.
